UNITED STATES PATENT OFFICE.

ASA H. BALLARD, OF FORT MORGAN, COLORADO.

BEET-TOPPING MACHINE.

1,368,471.

Specification of Letters Patent. Patented Feb. 15, 1921.

Application filed January 24, 1920. Serial No. 353,786.

To all whom it may concern:

Be it known that I, ASA H. BALLARD, a citizen of the United States, residing at Fort Morgan, county of Morgan, and State of Colorado, have invented certain new and useful Improvements in Beet-Topping Machines; and I do declare the following to be a full, clear, and exact description of the invention, such as will enable others skilled in the art to which it appertains to make and use the same, reference being had to the accompanying drawings, and to the characters of reference marked thereon, which form a part of this specification.

The object of this invention is to provide a cheap and efficient machine for topping beets, which may be operated with a minimum of power.

Briefly, the invention comprises conveying means disposed on both sides of a truck, and cutting means coöperating with the two conveying means. The cutting means and conveyers are brought into operation alternately in order that the application of power to each conveyer will not have to be continuous. Each conveying means comprises two endless members, one of which is shorter than the other. One member is provided with pockets for receiving the bodies of the beets, and the other with coöperating pockets for receiving the tops.

The cutting means operates between these two members, the severed tops remaining in the pockets in the one member. By reason of the difference in lengths of the two conveyer members, the tops are discharged at one point and the bodies at a different point.

In the drawings:

Figure 1 is a side elevation showing the invention.

Fig. 2 is a plan, the cutting means *per se* being omitted.

Fig. 3 is an enlarged elevational detail of the cutting device and is indicated by the arrow 3 of Fig. 4.

Fig. 4 is a face view, indicated by the arrow 4 of Fig. 3.

Fig. 5 is an enlarged detail taken from the line 5—5 of Fig. 2.

A framework 10, mounted upon a truck, carries an engine 12, provided with flywheels 14 and a sprocket 16, which drives a gear 20 through the medium of a chain 18. The gear 20 is mounted upon a crank shaft 22, having a pair of oppositely disposed

cranks 24, with which links 26 are connected. The links 26 are in turn pivotally connected with arms 28, fixed on two short shafts 30 and 32, whose inner ends are journaled in a common bearing 34, and whose outer ends are journaled respectively at 36 and 38. In this manner the two shafts 30 and 32 are operated independently. Each of the shafts 30 and 32 has fixed thereon a ratchet 40 and a gear 42. A dog 44 is pivoted on each arm 28 and engages the respective ratchet 40, each dog being pressed by springs 46. From this it will be seen that each link 26 imparts an oscillatory movement to the respective arm 28, which in turn imparts through the medium of the dog 44 partial rotation to the ratchet 40 and gear 42. Each gear 42, through the medium of a chain 48, drives a sprocket 50, which sprockets 50 are mounted on separate shafts 52 having a common journal 53. The shafts 52 thus have independent movement. To the outer end of each shaft 52 is fixed a gear 55, which drives a chain 54, which passes over one of a pair of gears 56, mounted on each of the short shafts 58 at the opposite end of the framework 10. The other one of each pair of gears 56 has a chain 60 passing thereover, and thence toward the opposite end of the machine to another gear 62. The chain 60 is shorter than the chain 54, as indicated. The chain 54 is provided with a plurality of blocks 64, shaped as indicated, to accommodate the bodies of the beets; and the chain 60 is provided with a plurality of blocks 66 to receive the tops of the beets. These chains with their respective blocks constitute the conveyers.

The blocks 64 are spaced somewhat from the blocks 66 and the cutting blade 70 reciprocates between the blocks. This blade is carried on the lower end of an arm 72, which operates in a vertically disposed guide 74, on a bracket 75, connected with the framework of the machine. The upper end of the rod 72 carries a link 76, eccentrically pivoted at 78 on a disk 80, fixed upon and rotated by the crank shaft 22. The rod 72 is provided with a lateral extension 82, which engages a forked beet-holding member 84, reciprocating in a guide 86, in the bracket 75. A spring 88 is interposed between the extension 82 and an offset on the member 84, this spring being provided in order that the holder 84 may yield accord-

ing to the size of the beet being held. This specific mechanism is described and claimed in my copending case, Serial No. 306,169, filed June 23rd, 1919.

5 From the foregoing it will be seen that the crank shaft 22 is rotated continuously by means of the chain 18. This rotation through the medium of the links 26 will cause the gears 42 to be rotated intermittently, with the result that intermittent motion will be imparted to the conveyers. This motion will take place on the upstroke of the links 26. Since the cranks 24 are oppositely disposed, the oscillation of the arms 28 and corresponding intermittent movement of the gears 42 and conveyers on opposite sides of the machine will be alternate. Thus the power of the engine will be employed first to move the conveyers on one 10 side of the machine, and then to move those on the other side. The reciprocation of the knives 70 through the medium of the crank shaft 22 and the disks 80 will be continuous, but it is so timed that the downstroke 15 of each knife will occur during the pause in the movement of the adjacent conveyer. The knives may be of sufficient length to top a plurality of beets at each stroke, as indicated in the drawings. After the top- 20 ping step, the beets and tops will lie in the respective pockets until the conveyer parts pass around the gears 55 and 62, the tops being discharged at a point adjacent the 25

knife 70, while the bodies are discharged beyond the end of the truck.

35

I claim:

1. In a beet-topping machine, spaced conveyers to carry beets, means to move said spaced conveyers alternately, and means to sever the tops from the beets on each conveyer, said severing means being operable during the interval between movements of the respective conveyers.

2. In a beet-topping machine, spaced conveyers to carry beets, means to move the 45 conveyers alternately, and alternately operating means to sever the tops from the beets on the respective conveyers.

3. In a beet-topping machine, spaced conveyers for the beets, means to move the conveyers alternately, and means adjacent each conveyer to sever the tops from the beets 50 thereon.

4. In a beet-topping machine, spaced conveyers for the beets, means to move the conveyers alternately, means to sever the tops from the beets, said conveyer-moving means comprising a crank shaft having oppositely disposed cranks, links on said cranks, a driving member for each conveyer, and a connection between each member and one of said links whereby movement is imparted to each member during movement in one direction 55 of the respective link.

In testimony whereof I affix my signature. 65
ASA H. BALLARD.
